UNITED STATES PATENT OFFICE.

THOMAS C. CHRIST, OF READING, PENNSYLVANIA, ASSIGNOR TO CRESCENT BRASS MFG. CO., OF READING, PENNSYLVANIA, A CORPORATION OF PENNSYLVANIA.

DESIGN FOR A SWIVEL JOINT FOR LIGHTING FIXTURES.

Application filed August 7, 1925. Serial No. 14,340. Term of patent 7 years.

To all whom it may concern:

Be it known that I, THOMAS C. CHRIST, a citizen of the United States, residing at Reading, in the county of Berks and State of Pennsylvania, have invented a new, original, and ornamental Design for Swivel Joint for Lighting Fixtures, of which the following is a specification, reference being had to the accompanying drawing, forming part thereof.

Fig. 1 is a side view, slightly in perspective, showing my new design.

Fig. 2 is a bottom plan view.

I claim:

The ornamental design for a swivel joint for lighting fixtures, as shown.

THOMAS C. CHRIST.
